UNITED STATES PATENT OFFICE.

CHARLES R. UHLMANN, OF PEORIA, ILLINOIS.

LOCK AND LATCH.

SPECIFICATION forming part of Letters Patent No. 496,497, dated May 2, 1893.

Application filed October 18, 1892. Serial No. 449,255. (No model.)

To all whom it may concern:

Be it known that I, CHARLES R. UHLMANN, a citizen of the United States, residing at Peoria, in the county of Peoria and State of Illinois, have invented certain new and useful Improvements in Mortise and Rim Locks; and I do hereby declare the following to be a full, clear, and exact description of the invention, such as will enable others skilled in the art to which appertains to make and use the same.

This invention relates to improvements in locks, of that class ordinarily used on doors and known as mortise and rim locks.

The object of the invention is to provide a safe guard, to render ordinary locks secure against being picked by hooks, wires or the like, all of which will be fully understood after considering the specification and drawings forming part of this application.

In the drawings, Figure 1 represents side view of the interior of a rim-lock showing my attachment applied thereto. Fig. 2 represents a side view of the key used on this lock. Fig. 3 is a perspective view of a catch used in my device for closing the key-hole. Fig. 4 is a perspective view of a key guide used in my lock. Fig. 5 is a plan view of the key guide described in Fig. 4. Fig. 6 is a transverse sectional elevation of the lock on the line xx Fig. 1. Fig. 7 is a side view of the interior of a mortise-lock showing a differently constructed device, applied to one of my locks, but embodying the same principle.

In the several figures, (with the exception of Fig. 7) A represents the lock-case, and a represents the usual snap catch which is actuated by the usual knob spindle which is inserted in the aperture a' , while c is the spring for keeping the said snap catch thrown outward, and b represents the locking-bolt which is thrown in and out by the ordinary key, and d is the tumbler. This construction is rather like an ordinary lock. Now what I term as a "guard and key-guide" and designated by A' is made in the peculiar shape shown in order that the upper portion of the key-hole may be left free by forming in the said "guard" the indentation 1 and the indentation 2 is made to allow of a key-hole closer B, which is located in the bottom of the lock, to enter it

in order that the key-hole may be closed, while the upper arched edge is so formed as to allow the tumbler or tumblers to operate freely. A post j is cast with the lock-case, and 55 a notch k is made in the upper body of the said guard which just allows the guide to enter between the said post j and the bottom flange of the lock. This mode of securing the guide, I do not however confine myself to, but 60 screws or rivets may be used instead. The upper portion of this guard A' occupies a position immediately between the locking-bolt and the tumbler, at the same time allowing the parts to work freely.

The block B already mentioned used for closing the key-hole is used in my several prior patents in some form or other, hence I do not claim that portion of this patent, except that with the free end thereof is cast an 70 ear or lug C as shown which in the position shown in Fig. 1 also forms a guide for the key in its rotary movement.

It will be seen that the guide portion of the block or guide A' occupies a position midway 75 between the two sides of the lock-case as also does the lug C of the block B.

The form of key used is shown in Fig. 2, with the depending ears E E with the slot F between them. The ears E E swing in the 80 space between the guide A' (Fig. 6) and either side of the lock-case, while the slot F must necessarily engage with the said guide. By this means it must be seen that the key may reach the locking-bolt and tumbler as easily 85 as in the old style of locks, and at the same time, the lock cannot in any possible manner be picked on account of the guard A'.

The block B is used as in my other locks by throwing it past the key-hole to prevent 90 the key being turned from the outside. The block is kept in place by a lug f (Fig. 1) cast with the rim of the lock case which engages with a notch g in the said block, and when the block covers the key-hole the end g' rests 95 behind the said lug f, and the spring h and head i bearing against the lip l (cast with the lock-case) keep the said block B down to its place.

The guide A' and lug C may be made with 100 a lip or flange 3 and 4 respectively cast on one or both sides thereof or in some similar

shape applied at one or more different places to prevent the use of any other key than the one especially designed for that lock.

In Fig. 7, b' represents the locking-bolt, d'' the tumbler and B' the key-hole closer and A^3 shows a different form of guide for the different shaped lock but in other respects the device is the same.

The sliding block B Fig. 7 may be placed 10 on the opposite side of the key-hole by cutting said block in two and using the end bearing the lug C and the said lug C may be made to curve up over the key-hole as the guard A' does, instead of the shape it now has, to take 15 the place of the block A' Fig. 1 and A^3 Fig. 7.

What I claim as new, and desire to secure by Letters Patent, is—

In a mortise or rim lock, the combination

with the case A, the bolt b and tumbler d , of the movable sliding block B with the lug C, 20 said block being held by the spring h , the guide A' of the form of an inverted L having the indentation 1, the indentation 2 to admit the lug C of the block B, said guide A' occupying a position between the bolt b and tumbler d respectively to prevent the picking of the lock and all being substantially of the form shown and all working together in the manner and for the purposes described. 25

In testimony whereof I affix my signature in 30 presence of two witnesses.

CHARLES R. UHLMANN.
